UNITED STATES PATENT OFFICE.

WILLIAM G. HOUSKEEPER, OF NEW YORK, N. Y., ASSIGNOR TO WESTERN ELECTRIC COMPANY, INCORPORATED, OF NEW YORK, N. Y., A CORPORATION OF NEW YORK.

ELECTRON-DISCHARGE DEVICE.

Application filed July 13, 1920. Serial No. 396,014.

To all whom it may concern:

Be it known that I, WILLIAM G. HOUSKEEPER, a citizen of the United States of America, residing at New York, in the county of New York, State of New York, have invented certain new and useful Improvements in Electron-Discharge Devices, of which the following is a full, clear, concise, and exact description.

10 This invention relates to electron discharge devices, more specially of the audion type, and its object is a device of large power output and one capable of dissipating a large amount of heat.

15 The invention provides an electron discharge device in which a portion of the evacuated vessel or envelope is of metal and serves as the anode. This metal portion is preferably in the form of a cylindrical copper cup, and its rim is fused or welded directly to a glass portion which forms the remainder of the envelope, and serves as a support for the other electrodes, the seal being formed in such a way as to resist rupture in spite of any inequality in the coefficients of expansion of the metal glass portions.

20 Such device is capable of handling large amounts of power effectively for the reason that the metallic portion of the envelope may be immersed in a suitable cooling fluid to conduct away from the anode excess heat generated therein.

25 Permanency of the seal between the metal and glass portions is obtained by insuring that no thick or unyielding part of the metal portion becomes imbedded in the glass during the fusing operation. In the preferred construction, this condition is realized by tapering the metal portion at the sealing point to a very thin edge so that even if the glass should flow over the edge in sealing the internal stresses in the imbedded portion will be insufficient to resist the surface adhesion between the glass and metal so that the seal will remain intact in spite of any inequality in the coefficients of expansion of the metal and glass.

30 The invention is illustrated in the drawings, of which Fig. 1 represents a longitudinal section through the containing vessel, showing the other parts in elevation; Fig. 2 represents an enlarged detail view of part

of the support for filament and control electrodes; Fig. 3 represents a detail view of another part of the above mentioned electrode support; and Fig. 4 represents a part sectional view of the manner in which the electron discharge device is cooled.

35 As shown in the drawings the device comprises a cup-shaped vessel 1 of metal, preferably of copper, which is adapted to serve as one of the electrodes of the device, preferably the anode. Electrical connection may be made to anode 1 by simply fastening a wire, such as a wire 2 to the outside of the electrode. The rim of the anode is preferably flared outwardly, and is tapered to a very thin edge 3. In one type of electron discharge device made in accordance with this invention, the cylindrical portion of the anode is about 6" long, 1½" in diameter, and its wall is 3/16" thick. The rim of the anode is flared outwardly for approximately 1½" to a diameter of about 2" and is tapered to an edge of approximately .008".

40 The end of the anode is sealed to a base portion 4, preferably made of glass according to the method disclosed in my U. S. Patent No. 1,294,466, issued February 18, 1919. In the manufacture of the device a length of glass, 5, preferably potash glass, about a half an inch in length is made with a flare substantially corresponding to the flare of the anode. This portion of glass and end of the anode are then inserted in a flame and fused together. After this the portion 4 is fused to the portion 5.

45 The manner in which the glass and metal portions are fused together renders the seal permanent as it prevents the imbedding of any substantial amount of the metal in the glass.

50 The other electrodes are supported within the metallic anode on a framework. This framework comprises a hollow rod or arbor 6, preferably seamless steel tubing, each end of which is formed to a square section. The end 7 which is of considerable length, passes through an aperture 8 in a plate of insulating material 9, preferably of "lavite" and is positioned relative to said plate by the engagement therewith of the shoulder between the squared and round sections. Two plates 11 and 12 are bent around the end 7 and a

spacing sleeve 13' is positioned between the edges of the plates 11 and 12 and the face of the plate 9.

The outer ends of the plates 11 and 12 are welded to upright T-bars 13 and 14 which in turn at their lower ends are welded to a collar 15 which surrounds and grips the stem 16 of the glass base 4 of the vessel. The plates 11 and 12, the bars 13 and 14, and the collar 15 are all made preferably of nickel.

The other end of the arbor 6 fits tightly into and passes through apertures (not designated) in plates 17 and 18 both preferably of "lavite". The plate 18 is slightly larger in diameter than the plate 17 and is adapted to fit loosely within the anode 1, thus positioning said end of the arbor 6 centrally with respect to the anode 1. This end of the arbor 6 is split into strips 32 which are bent over on to the outside surface of the plate 18. The lower face of the plate 18 is provided with a flange 20, preferably of "lavite" which serves to space it from the plate 17, and thus increase the electrical leakage path between conductors in plate 17 and the point of contact between anode 1 and plate 18. A plurality of wires 21 are fastened in the plate 17 and extend loosely through apertures in the plate 9. To these wires a spirally wound length of wire 22 forming the control electrode is welded throughout its length. This wire 22 is preferably made of nickel. The loose mounting of the wires 21 in the plate 9 permits them to expand under the influence of heat. One of the control electrode supporting wires 21 is connected to a lead-in wire 23 which passes through a long tubular extension 24 of the stem 16 and is sealed through the end of the same. The tubular extension 24 is also evacuated so that wire 22 is separated by the vacuum from the other lead in wires which pass out of the vessel on the outside of the tubular extension 24. By this means high voltage discharges between the lead-in wires is prevented. This feature is claimed in my U. S. Patent 1,536,855, issued May 5, 1925.

A filament 25 is supported and wound in a zigzag fashion between the "lavite" plates 9 and 17. At one end it is supported by a plurality of hooked wires 26 which are fastened in apertures in the "lavite" plate 17. At its other end, it is connected to a plurality of hooked wires 27 which pass loosely through apertures in the "lavite" plate 9. The shanks of the hooks 27 are welded to the outer ends of coiled springs 29. Each spring 29 has two portions of different dimensions, the portion 30 of small dimension being coiled to fit the aperture 31 in the "lavite" plate 9 and through which the wire 27 passes. This type of design in connection with filaments is described more in

detail in a copending application Serial No. 340,455, filed November 25, 1919, entitled Vacuum tubes in the name of Paul M. Watrous. By this means the filament is kept in a state of constant tension under the varying temperatures to which it is subjected. These springs are preferably placed as shown on that side of plate 9 remote from the main part of the electrode structure so that they are effectively shielded from the heated area. The effect of the heat on the elasticity of the springs is thereby substantially avoided. One end of the filament is connected to one of the wires 26 which passes through an aperture in plate 18 and is welded to one of the strips 32 into which the upper end of the rod 6 is divided and which are bent over against a face of the plate 18 to clamp it against the plate 17. By means of this connection through the rod 6, the plates 11 and 12, the T-bar 13, a connecting wire 33 and a lead-in wire 34 the electrical connection to this end of the filament is established. The other end of the filament is connected to one of the wires 26 which passes through the plate 18 and extends into an insulating tube 35 preferably of glass or quartz disposed within the hollow steel arbor 6. This tube 35 extends to a point beyond the square end 7 of the arbor 6. The connecting wire 35' for this end of the filament passes through the tube 35 and is welded to the end of the lead-in wire 36.

This device is particularly adapted for operation with large amounts of energy. The particular structure described has been found capable of absorbing three kilowatts of energy at a voltage of 3500 on the anode. The tube when operating with such large amounts of power is adapted to be used as a modulator, an oscillator or an amplifier in electrical systems such as telephone and radio circuits. One way the tube may be connected up as an amplifier of electric currents is shown in the Arnold Patent #1,129,942, of March 2, 1915.

When such large amounts of power are being applied to the tube it is necessary that a simple and effective means be provided to dissipate the heat generated at the anode. To this end, Figure 4 illustrates a simple and efficient cooling system which is adapted to be used in connection with this thermionic device. As shown in the figure it comprises a receptacle 40 which has an inlet 41 and an outlet 42 for the circulation of a cooling medium which may be water or oil or other suitable medium. Or it may be advisable to provide a different cooling means such as a coil or pipe 43 through which a cooling medium may be passed. This coil or pipe is disposed around the space occupied by the metallic anode of the tube. The bottom of receptacle 40 is provided with an aperture

which is partly closed by means of washer 44 of leather or heavy rubber or the like fastened to the bottom of the vessel by means of brass rings 45 and screws 46. The thermionic device is inserted through the opening in the washer 44 and is positioned there in so that about half of the lower glass portion of the base of the device extends into the receptacle 40. The lower end of the tube 10 extending below the bottom of receptacle 40 is readily accessible for making electrical connections thereto, the bottom of receptacle 40 being elevated from the level of the floor of the platform on which it is placed by means of standards 47. This arrangement 15 is suitable when water or other conducting medium is used for cooling since the leads at the lower end of the device are thus insulated from the conducting cooling medium. 20 When however, oil or other insulating medium is used for cooling the device, it is not necessary to employ a receptacle having a special aperture as shown in Fig. 4 since all the lead in conductors may be immersed in the oil without any danger of electrical leakage taking place.

It will be apparent from consideration of the above description of the mechanical construction of this tube that the mounting for the filament and grid and the supporting connections from this mounting to the stem of this tube can be and are completely assembled as a unit before this unit is fastened to the stem 16. It will also be readily apparent that this tube is not only capable of absorbing large amounts of power in a simple and efficient manner but that the structure is rigid and capable of standing up under severe usage, compared with the ordinary radiation type of tube in which the heat generated is dissipated merely by radiation from the electrodes within a glass bulb.

What is claimed is:

1. A high power electron discharge device comprising a container and a cathode supported therein, said container comprising two portions, one of metal forming the anode, and the other of vitreous material supporting the cathode, the said portions of said container being directly sealed together by fusion, and the meeting surfaces of said portions being so shaped with respect to each other that no unyielding part of said metal portion can become imbedded in said vitreous portion during the fusing operation, whereby rupture of the seal because of unequal coefficients of the expansion of the two portions is prevented.

2. An electron discharge device comprising a containing vessel, a stem, a rigid bar, insulating plates secured to the ends of said bar, an electrode supported by and between said plates, a second electrode resiliently supported by and between said plates and positioned within said first mentioned elec-

trode, and a metallic support connecting said unit with said stem.

3. An electrode unit comprising a rigid hollow metallic bar, insulating plates fastened to each end of said bar, a control electrode supported between said plates a cathode supported between said plates and positioned within the control electrode, means on one of said plates and connecting with one end of said cathode for resiliently supporting the same, a hollow insulating tube supported within said metallic bar, a connection from one end of said cathode to said hollow bar and another connection on the other end of said cathode adapted to pass within said hollow insulating tube, both of said connections being adapted to lead to a suitable source of potential.

4. An electron discharge device having a containing vessel comprising a hollow metallic portion and a hollow glass portion fused together, a receptacle into which the device may be inserted, an aperture in said receptacle through which the device passes, a flexible washer in said aperture adapted to engage a surface of said device and cooling means within said receptacle to cool the device.

5. An electron discharge device comprising a cup-shaped metallic portion, a glass portion supported by said metallic portion and forming an enclosing vessel, a stem projecting from said glass portion into said vessel, a metal collar surrounding said stem and supported thereby, a metallic member supported from said collar, and a plurality of electrodes surrounding said member and supported thereby.

6. An electron discharge device comprising a cup-shaped metallic portion, a glass portion supported by said metallic portion and forming an enclosing vessel, a stem projecting from said glass portion into said vessel, a metal collar surrounding said stem and supported thereby, a metallic member supported from said collar, a plurality of insulating blocks carried by said member, and a plurality of electrodes surrounding said member and supported by said insulating blocks.

7. In an electron discharge device, a metallic member, an electrode surrounding said member and supported thereby, a second electrode surrounding said first electrode, and means carried by said metallic member to engage said second electrode to determine the space relation between said electrodes.

8. An electron discharge device comprising a containing vessel, a cup shaped anode constituting a portion of the containing wall of said vessel, said anode being flared at its open end, a glass portion for closing the flared end of said anode, and welded thereto, a stem in said vessel and a cathode supported by said stem.

9. An electron discharge device comprising a stem, an electrode above said stem, means for rigidly supporting that end of said electrode remote from said stem, and guiding means at that end of said electrode adjacent said stem for spacing said electrode while still permitting expansion and contraction of said electrode. 70
10. An electron discharge device comprising a stem, anode, cathode and grid electrodes above said stem, means for rigidly supporting that end of said grid remote from said stem and guiding means comprising an apertured plate for spacing said grid while permitting the free expansion or contraction thereof. 75
11. An electron discharge device comprising a stem, cathode and grid electrodes above said stem, a resilient support for that end of said cathode adjacent said stem, means for rigidly supporting that end of said grid remote from said stem, and guiding means for the other end of said grid for permitting said grid to expand or contract, said guiding means being interposed between said resilient support and the main portion of said electrodes. 80
12. In an electron discharge device, a metallic member, a cathode supported thereby, a grid electrode comprising a plurality of longitudinal wires supporting a wire helix, and a block of insulating material carried by said metallic member and engaging one end of said wires. 85
13. An electron discharge device comprising a plurality of electrodes, a plurality of blocks of insulating material for supporting said electrodes, a spacer for said blocks, and a lead in wire for one of said electrodes passing through said spacer. 90
14. In an electron discharge device, a metallic member, a cathode surrounding said metallic member and supported thereby, a grid electrode comprising a plurality of wires rigidly mounted at one end and arranged parallel to said member, a lateral wire supported by said longitudinal wires, and a block of the insulating material carried by said metallic member and engaging the other ends of said wires. 95
15. An electrode assembly comprising a metallic rod, insulating plates at either end of said rod, a cathode and a grid interposed between said plates, said electrodes being rigidly attached to one of said plates and being slidably supported by the other of said plates to permit the free expansion or contraction thereof. 100
16. An electron discharge device comprising an enclosing vessel having a reentrant stem, a collar surrounding said stem, a grid electrode supported from said collar and comprising a plurality of rods supporting a wire helix, a metallic member within said grid electrode, a cathode surrounding said 110
17. In an electron discharge device, a metallic member, a cathode supported by and surrounding said member, a grid electrode surrounding said cathode, said grid electrode comprising a plurality of longitudinal supporting wires and a wire helix, and a block of insulating material carried by said metallic member and engaging a portion of said grid electrode to maintain the space relation between said grid electrode and said cathode. 115
18. In an electron discharge device, a metallic member, a cathode supported thereby, a grid electrode comprising a plurality of longitudinal rods supporting a wire helix, and a block of insulating material carried by said metallic member and engaging said rods to maintain the space relation between said grid electrode and said cathode. 120
19. An electron discharge device comprising an enclosing vessel having a reentrant stem, a metallic member supported at one end from said stem, a cathode surrounding said metallic member and supported thereby, a cylindrical electrode surrounding said cathode, and means carried by said metallic member at its opposite end to engage a portion of said electrode to maintain the space relation between said cathode and said other electrode. 125
20. In an electron discharge device, a metallic member, a cathode surrounding said metallic member and supported thereby, a block of insulating material carried by said member, and a grid electrode having one end fixed and the other end slidably engaging said block to permit free expansion and contraction of said electrode. 130
21. In an electron discharge device, a metallic member, a block of insulating material carried by said metallic member, a cathode supported by said metallic member, and a substantially cylindrical electrode surrounding said cathode, said electrode having one end fixed and the other end slidably engaging said block of insulating material to permit free expansion or contraction of said electrode. 135
22. An electron discharge device having a reentrant stem, a collar surrounding said stem, a grid electrode supported from said collar and comprising a plurality of rods supporting a wire helix, a cathode within said grid electrode, and means comprising a block of insulating material engaging one end of said grid electrode to maintain the space relation between said cathode and said grid electrode. 140
23. An electron discharge device comprising a pair of blocks of insulating material, 145

means for supporting said blocks, a cathode between said blocks, means carried by one of said blocks for rigidly supporting one end of said cathode, resilient means carried by the other of said blocks, and a member supported by said resilient means and connected to said cathode, said member passing through said second block whereby said block acts as a heat shield for said resilient means.

10 24. An electron discharge device comprising a pair of blocks of insulating material, means for supporting said blocks, a cathode between said blocks, rigid members carried

by one of said blocks for supporting one end of said cathode, and resilient means carried by the other of said blocks for supporting 15 the other end of said cathode, said resilient means comprising a wire helix and a member supported by said helix and connected to said cathode, said member passing through said block whereby said block acts as a heat 20 shield for said helix.

In witness whereof, I hereunto subscribe my name this 2nd day of July A. D., 1920.

WILLIAM G. HOUSKEEPER.
